HAIR CURLER WITH ROTATABLY
ADJUSTABLE BARREL

Albert E. Vaughn, Orange, N. J.

Application September 14, 1950, Serial No. 184,727

8 Claims. (Cl. 132—42)

1

This invention relates to hair curling devices and particularly to that type of hair curler which comprises an elongate body or barrel around which locks of hair are wound to form curls, and means for maintaining the curls in place to prevent unwinding thereof.

Various types of devices have been provided for temporarily curling or waving hair without the application of heat. The most common type of curler, commonly referred to as a "Hollywood curler," consists of a cylindrical metal tube or barrel and a metal clamp pivoted to one end of the tube, the end of the lock of hair being inserted between the tube and clamp and then wound tightly around these two parts. A substantially U-shaped clip pivoted to the same end of the tube as the clamp is adapted to fold down over the wound lock of hair, being provided with a resilient disc roller rotatably mounted on the outer looped end of the clip and adapted to be received within the end of the tube to yieldingly lock the parts in closed position. Curlers of this type are usually constructed from metal and the U-shaped clip has inturned ends which pass through aligned holes in the tube and clamp with their terminal portions deformed within the tube to assemble the parts in hinged relationship.

It is a known fact that when such relatively rigid metallic hair curlers are used the sharp edges of the clamp often break or cut the ends of the hair and when they are worn in the hair during repose the pressure of the curlers against the head is uncomfortable and tends to disturb the sleep of the wearer. Moreover, such conventional hair curlers are composed of several parts which must be carefully assembled and it is the usual practice to employ special tools for flattening the inner ends of the clip within the tube to secure the parts together and this adds to the over-all cost of manufacture. Furthermore, it has been determined that when such curlers are used the parts often become bent or broken and the clip frequently loses its resiliency thereby rendering the curler unfit for use.

It is one object of my invention to provide a hair curler of simplified construction which comprises only two parts, namely, a combined body member or barrel and clamp member, and an elastic clip member carried by the barrel and foldable into position therealong.

Another object is to provide a hair curler of the type indicated in which the combined barrel and clamping member is constructed from semi-flexible material and in which the clip member is made from resilient, flexible, elastic or other

2

deformable material, thereby permitting the curlers to be worn with comfort during repose.

Another object is to provide a hair curler in which the barrel and clamp are adapted to be molded in one piece, thus eliminating the usual stamping and bending operations and avoiding the use of special tools and the exercise of special skill in assembling the parts.

Another important object of the invention is 10 to provide a hair curler, of the character referred to, in which the clip member has an integrally formed annular loop portion at one end adapted to snap into a peripheral groove disposed at one end of the body member. By this construction, 15 the body member and clip member are connected for relative rotation so that by holding the clip member in one hand the body member can be rotated with the other hand so as to wind locks of hair thereon without twisting the hair.

Another object is to provide a hair curler of 20 the class specified in which the body member is made from a semi-resilient material and has a keeper opening in its end opposite the end having the peripheral groove, the clip member having 25 a detent lug or key at its free end adapted to snap into said opening so as to retain the clip member in closed position in overlying relation to the body member and thus retain the hair in place surrounding the body member.

Another object is to provide a hair curler in 30 which the clip member is of an elastic nature so that it can be stretched or elongated longitudinally to facilitate insertion of its locking lug in the keeper opening. By this provision, the 35 inherent tendency of the clip member to contract longitudinally effects frictional resistance to rotation of the body member after the parts are closed together, so that displacement of the lock of hair from the device is prevented.

Another object is to provide a body member 40 in which the keeper opening and the locking lug are non-circular in cross section so that the clip and body members are keyed together to further guard against relative rotation of the parts when the device is closed. Preferably, the keeper opening is made multi-sided so that the locking lug of the clip member may engage therein in any of several positions.

In another form of the invention, the opening may take the form of a 45 plurality of crossing slots in the end of the body member in any of which the locking lug may engage.

A still further object is to provide a hair curler 50 in which the body member is provided with an integral, resilient, clamping portion or finger un-

der which the end of a lock of hair may be placed and retained at the start of the operation of winding the hair on the body member. As a feature of improvement, the body member is provided with a longitudinally extending groove or recess into which the clamping finger is depressible so that the over-all width or thickness of the body member is maintained at a minimum.

Further objects of the invention will appear from the following description and from the drawing, which is intended for the purpose of illustration only, and in which:

Fig. 1 is an enlarged perspective view of my improved hair curler, showing the parts in closed relationship;

Fig. 2 is a front elevational view of the hair curler showing the body member rotated through 180° from the position shown in Fig. 1;

Fig. 3 is a plan view of the curler;

Fig. 4 is a cross-sectional view, taken on line 4—4 of Fig. 2;

Fig. 5 is a cross-sectional view, taken on line 5—5 of Fig. 2;

Fig. 6 is a view similar to Fig. 3, but on a reduced scale, illustrating the manner of opening the device for the reception of the end of a lock of hair;

Fig. 7 is a side view of a hair curler of slightly modified construction; and

Fig. 8 is an enlarged cross-sectional view, taken on line 8—8 of Fig. 7.

Referring to the drawing in detail, my improved hair curler device includes an elongate spindle or body member 10 which is preferably molded from a semi-flexible plastic material. The spindle 10 is herein shown as of square cross section and its sides are concavely curved in a longitudinal direction. Formed integrally with the spindle 10 is a clamping portion or finger 11 which is connected to the spindle at one end 12 thereof and which overlies a cut away portion or recess 13 provided in one side of the spindle. The clamping finger 11 is resilient and thus may be flexed outwardly from the recess 13 as shown in Fig. 6 to insert the end of a lock of hair in the recess, after which the finger may be released to cause it to flex inwardly so as to clamp the end of the lock of hair against the spindle prior to winding the hair thereon. The sides of the body member 10 preferably have longitudinal depressions 15 into which the hair may be depressed to effect a secure grip thereof around the member.

The end 12 of the body member or spindle 10 is reduced in cross section to provide an axial extension formed with a conical head 16. Between the head 16 and the main portion of the spindle 10 the extension is provided with a peripheral groove 17. The other end 19 of the spindle 10 is provided with a recess or keeper opening 20 which, as shown in Fig. 5, may be of square or other multi-sided cross-sectional shape.

The hair curler device also includes a clip member 25 which is molded from resilient or elastic plastic material. The member 25 is in the form of a closed rectangular loop, having parallel side bars 26 joined at one end by a circular loop 27 and at the other end by an end bar 28. The loop 27 has a central aperture 29 of a diameter slightly larger than the diameter of the peripheral groove 17. Due to its elasticity, the loop 27 is expandable diametrically to adapt it to be forced over the conical head 16 of the spindle and to snap into the peripheral groove 17 to rotatably connect the clip member 25 to the body member 10. It is important to note, by reference to Figs. 1 and 3,

that the portions of the side bars 26 adjacent the loop 27 are curved as indicated at 30, the point of joinder of each side bar and the loop being offset above the axis of the loop. In addition, it will be observed by reference to Fig. 6 that the included angle α between the loop and the side bars 26 is made considerably less than ninety degrees for the purpose to be later explained.

The end bar 28 of the clip member 25 is provided with an inwardly directed resilient lug or key 33 of rectangular cross section (Fig. 5). When the clip member 25 is flexed toward the end 19 of the body member 10, the resilient key 33 rides across an edge bordering the keeper opening 20 and snaps into the opening to releasably lock the parts 10 and 25 in closed relationship and to resist rotation of the clip member. Preferably, the maximum dimension of the key 33 is made slightly greater than the minimum dimension of the keeper opening 20 so as to create frictional resistance to relative rotation of the clip member and the spindle. To open the device, the free end of the clip member is flexed away from the end 19 of the spindle and to facilitate prying of the end bar 28 from the end 19 of the spindle so as to flex the key 33 from the opening 20, the end bar is provided with transversely extending fingerpieces 34 adapted to be engaged by a fingernail of the user (Fig. 3).

To apply the improved hair curler to use, the clip member 25 is first opened as shown in Fig. 6, after which the finger 11 is flexed outwardly from the recess 13 as also shown in this view. The end of a lock of hair is next placed across the recess 13 and the finger 11 is thereafter released and allowed to flex inwardly, due to its inherent resiliency, so as to clamp the end of the lock of hair in the recess. With the end of the hair thus clamped to the body member or spindle 10, the latter is rotated by holding the clip member 25 between the fingers of one hand and turning the end 19 of spindle by the fingers of the other hand. By this procedure, the body member 10 is caused to roll along the scalp of the user so as to wind the lock of hair therearound.

After the lock of hair has thus been wound around the spindle 10, the clip member 25 is flexed toward the spindle to overlie the roll or curl of hair and to dispose its end bar 28 adjacent the end 19 of the spindle. By forcing the end bar 28 into alignment with the axis of the spindle 10, its resilient lug or key 33 is caused to ride across the edge of the end 19 and to snap into the keeper opening 20. It is to be noted at this point that during the forcing of the key 33 across the end 19 of the spindle, the clip member is stretched to a slight extent and its side bars 26 may tend to straighten. That is to say, the curved portions 30 may flatten somewhat to accommodate such stretching or elongation of the clip member into closed position. Due to the inherent resiliency or elasticity of the clip member, the key 33 is retained within the keeper opening 20. Since the longest dimension of the key 33 is slightly greater than the distance across the flats or sides of the opening 20, the key is compressed slightly and even though the key may assume a diagonal position extending between corners of the opening, the frictional engagement of the key in the opening will effectively resist relative rotation between the clip and body members. Since the clip member 25 possesses a relatively high degree of elasticity, its side bars 26 may flex laterally outwardly to follow the roll of

hair and to thus grip the same to further resist rotation of the spindle 10.

After the curler has been in use for a period sufficient to "set" the curl, the curler device is opened by merely flexing the end bar 28 of the clip member 25 so as to retract the key from the keeper opening 26. The clip member 25 then may be pivoted or, to be more specific, flexed away from the spindle or body member 10, the clip member then assuming the position shown in Fig. 6. The spindle is then rotated in reverse direction to unwind the lock of hair therefrom. The end of the lock of hair is removed from the device by merely withdrawing it from beneath the clamping finger 11.

Referring now to Figs. 7 and 8, my invention also contemplates the alternative construction shown therein. In this modified construction, the end 19 of the spindle or body member 10 is provided with a pair of crossing slots 40 and 41, each of which is adapted to receive the lug or key 33 of the clip member 25 when the latter is closed down against the body member. By this engagement of the key 33 in either slot 40 or 41, relative rotation between the clip and body members is resisted and raising of the clip member is prevented.

While I have herein disclosed the improved hair curler as embodied in two preferred forms of construction, it will be apparent that various modifications might be made which would fall within the scope of the appended claims.

I claim as my invention:

1. A hair curler, comprising: an elongate body member around which hair can be wound, said body member having a non-circular, keeper opening in its first end and a peripheral groove adjacent its second end; and a resilient clip member having an annular loop portion at one end surrounding said second end of said body member within said groove to allow relative rotation between said body member and said clip member, said clip member having parallel side bars extending longitudinally of and spaced from said body member and having an end bar extending across said first end of said body member, said end bar having an integral, non-circular latching lug adapted to snap into said non-circular keeper opening so as to releasably retain said clip member in closed position with its side bars extending alongside said body member and to resist relative rotation between said clip and body members, said side bars when unrestrained extending from said loop portion at an angle of less than ninety degrees so that upon release of said latching lug from said keeper opening, said side bars automatically assume an inclined relation to the axis of said body member due to the inherent resiliency of said clip member.

2. A hair curler, comprising: an elongate body member around which hair can be wound, said body member having a non-circular, keeper opening in its first end and a peripheral groove adjacent its second end; and an elastic clip member having an annular loop portion at one end surrounding said second end of said body member within said groove to allow relative rotation between said body member and said clip member, said clip member having parallel side bars extending longitudinally of and spaced from said body member and having an end bar extending across said first end of said body member, said end bar having an integral, non-circular latching lug adapted to snap into said non-circular keeper opening so as to releasably retain

said clip member in closed position with its side bars extending alongside said body member and to resist relative rotation between said clip and body members, said clip member being stretchable longitudinally to allow entrance of said latching lug into and removal thereof from said keeper opening, said side bars when unrestrained extending from said loop portion at an angle of less than ninety degrees so that upon release of said latching lug from said keeper opening, said side bars automatically assume an inclined relation to the axis of said body member due to the inherent elasticity of said clip member.

3. A hair curler of the character defined in claim 1 in which said body member has a flexible clamping finger extending alongside said body member in close association thereto and adapted to clamp end portions of locks of hair against said body member, said finger being adapted to flex outwardly from said body member to facilitate placing the end portions of the hair against said body member.

4. A hair curler of the character defined in claim 1 in which said body member has a flexible clamping finger extending from said second end alongside said body member toward said first end in close association with said body member and adapted to clamp end portions of locks of hair against said body member, said finger being adapted to flex outwardly from said body member to facilitate placing the end portions of the hair against said body member.

5. A hair curler of the character defined in claim 1 in which said body member has a longitudinally extending recess in a side thereof, said body member having a flexible clamping finger extending from said second end alongside said body member toward said first end in overlying relation to said recess.

6. A hair curler of the character defined in claim 1 in which said keeper opening is multi-sided and has a minimum transverse dimension and a maximum transverse dimension, and in which said latching lug has a transverse dimension slightly greater than said minimum transverse dimension.

7. A hair curler of the character defined in claim 1 in which said keeper opening is a transverse keyway and in which said latching lug is a transverse key engageable in said keyway.

8. A hair curler of the character defined in claim 1 in which said end bar, together with its latching lug is flexible relative to said first end of said body member so as to facilitate insertion of said lug into and removal thereof from said keeper opening, and in which said clip member has an integral fingerpiece on its said end bar for facilitating flexing of said end bar.
